(57) **CLAIM**

The ornamental design for a subwoofer for a home theater system, as shown.

DESCRIPTION

Subwoofer for a home theater system of which the following is a specification, reference being had to the accompanying drawings forming a part thereof.

FIG. 1 is a perspective view of a subwoofer for a home theater system showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.
